TELEPHONE SYSTEM

Frank Newforth, Jr., Temple City, Calif., assignor
to American Telephone and Telegraph Company, a corporation of New York

Application April 17, 1934, Serial No. 721,041

10 Claims. (Cl. 179—18)

This invention relates to telephone systems and particularly to systems of the class using automatic switching apparatus for establishing connections.

5 The objects of the invention are to more accurately identify the condition of a subscriber's line during the interval in which a switch, such as a finder or a line switch, is in the act of seizing or extending the line; to avoid the necessity of 10 rendering a line busy merely because the subscriber's receiver is off the switchhook; to reduce the number of calls that fail because the called subscriber delays in hanging up his receiver following a previous call; to enable all switches and 15 apparatus to be released immediately by the calling subscriber; and to otherwise improve systems of this character.

It has been the practice heretofore in systems employing switches of the step-by-step type to 20 release all switches except the final or connector switch when the calling subscriber hangs up his receiver and to hold the connector switch until the called party retires. It has also been proposed heretofore to place the release of all 25 switches, including the connector switch, under the control of the calling subscriber and to provide special means to prevent the called line from seizing the central office equipment in case the called party delays hanging up his receiver.

30 According to the present invention advantages are secured over these prior systems by allowing the calling subscriber to release all of the switches immediately and permitting the called subscriber's line to be seized by a finder switch 35 in the central office in case he does not replace his receiver at once.

A feature of the invention is an arrangement 40 in which the line of a subscriber, whose receiver is off the switchhook, as would be the case with a called party who has delayed replacing his receiver following conversation, is characterized in the multiple terminals of the connector switches as neither busy nor idle during the interval that the line is being hunted by a finder 45 switch. As soon as the finder reaches the terminals of the line, it is then identified as a busy line in the usual manner. Should, therefore, a connector switch seize the subscriber's line during the time the receiver is off the hook, and before 50 it has been seized by a finder switch, it will not appear as a busy line and, accordingly, no busy tone will be returned to the calling subscriber. Since the line does not appear to be idle, the connector switch will not apply ringing 55 current thereto in the usual way but will merely

wait on the terminals of the line. If the subscriber, whose line has been seized in this manner, hangs up his receiver before the calling party abandons the call, the connector will then proceed to apply ringing current and will thus call 5 the subscriber back to his telephone.

Another feature of the invention is an arrangement in a system of the character above described in which all switches involved in an established connection are released immediately 10 that the calling subscriber replaces his receiver.

These and other features of the invention will be more fully described in the following specification, taken in connection with the accompanying 15 drawing.

The invention is illustrated in the accompanying drawing in which Figure 1 shows a subscriber's station A, a line finder LF, a selector S in diagrammatical form, a connector switch C in detail another subscriber's station B and its associated line circuit, an associated line finder LF¹, and a selector S¹, in diagrammatical form. Fig. 2 shows an alternative line circuit that may be used instead of the one shown within the broken lines in Fig. 1. 25

The subscribers' stations A and B are provided with the usual subscriber's set with a dial for controlling the establishment of desired connections. The line-finder switches LF and LF¹ are of the well-known Strowger type and may be 30 similar to that disclosed in Patent 1,711,682 issued May 7, 1929 to H. Hovland, the brushes 8 and 9 of line finders LF and LF¹ respectively corresponding to one of the two sets of brushes shown in the Hovland patent. The selector switches S and S¹ are also of the well-known Strowger type and reference may be had to pages 35 to 67 inclusive of the 2nd edition of "Automatic Telephony" by Smith and Campbell for a detailed 35 description of the operation of the circuits associated with these switches. Only such portions of the circuits of the line finders and selectors are shown as are required for a clear and complete 40 description of this invention, the omitted portions of these circuits being represented by 45 broken lines.

Referring to the drawing, a description will 50 now be made of a call originating at subscriber's station A, over line 5, through line finder LF, selector S, connector C and over line 4 to a called subscriber's station B. When the subscriber A has been connected to the connector C through line finder LF and selector S in the usual manner, a circuit is completed through the subscriber's loop from ground through lower winding of 55

relay 1, upper back contact of relay 3, tip terminal and tip brush of selector S, tip brush and terminal of line finder LF tip conductor of line 5, through subset at station A, ring conductor of line 5, ring terminal and brush of line finder LF, ring brush and terminal of selector S, lower back contact of relay 3 and through the upper winding of relay 1 to battery. Relay 1 operates in this circuit and closes an obvious circuit for operating relay 2. Relay 2 operated connects ground to the sleeve terminal and brush of selector S for holding said selector in an operated position and for guarding the connector C from being seized by other hunting selectors.

15 The connector C is now ready for the reception of the dialing impulses which when dialed, by the calling subscriber, cause the line relay 1 to alternately release and reoperate each time the subscriber's loop is opened and closed at the dial.

20 The release of relay 1 in response to the first impulse closes a circuit from ground at the lower back contact of relay 1, upper front contact of relay 2, normally closed contact of vertical off-normal springs VON, and through windings of relay

25 6 and vertical magnet 7 to battery. Relay 6 and the vertical magnet will operate in this circuit, and the vertical magnet advances the brushes of this connector C one step. Relay 2 due to its slow-to-release characteristics holds during the

30 receipt of the remaining impulses of the impulse train.

As soon as the shaft of connector C is moved off-normal the vertical off-normal springs VON are actuated to open the aforementioned operating circuit for relay 6 and magnet 7 and to close an independent operating circuit for said relay and magnet through the front contact of relay 6. The reoperation of relay 1 releases magnet 7, but relay 6 due to its slow-to-release characteristics

35 remains operated until all of the impulses of the impulse train are received. Each successive release and reoperation of relay 1 causes the operation and release of magnet 7, thereby advancing the brushes of the connector C step-by-step to the level through which the call may be extended toward the called station.

When all of the impulses, corresponding to the digit dialed, have been received, relay 6 and vertical stepping magnet 7 release. Relay 6 released

50 closes a circuit for energizing rotary magnet 10 and relay 11 when relay 1 releases for the first impulse of the next series of dialing impulses. This circuit may be traced from ground at lower back contact of relay 1, upper front contact of relay 2, lower closed contacts of vertical off-normal springs VON, back contact of relay 6, right outer back contact of relay 12, thence in parallel; one path extending through the winding of relay 11 to battery; and the other extending through

55 lower next to inner back contact of relay 13 and through rotary stepping magnet 10 to battery. Relay 11 in operating closes a circuit, at its right front contact, for maintaining an operating circuit for itself and magnet 10 independently of the right outer back contact of relay 12. Relay 11 also connects the test relay 12 to the

60 sleeve conductor 17 to prepare the connector for a busy test when the terminals of the called subscriber's line have been seized. The rotary magnet 10 operated rotates the shaft and brushes of connector C to the first set of terminals in the selected level. The reoperation of relay 1 releases magnet 10, but relay 11 is slow-to-release and is designed to remain operated until all of

65 the impulses of the impulse train are received.

Each successive release and reoperation of relay 1 causes the operation and release of magnet 10, thereby advancing the brushes of the connector C step-by-step to the terminals associated with the called subscriber's line.

When all of the impulses corresponding to the last digit have been received, relay 11 and magnet 10 release. However, relay 11 is slow-to-release as aforementioned and remains operated for a sufficient length of time to initiate the aforementioned busy test of the called subscriber's line. If the line is busy, a ground will be found on the sleeve terminal of this line. This results in an operating circuit for test relay 12 from said ground, sleeve brush of connector C, sleeve conductor 17, left front contact of relay 11, lower next to outer back contact of relay 13 and through winding of relay 12 to battery. Relay 12 operated prepares a locking circuit for itself which is effective when relay 11 releases. This circuit is traceable from ground at lower outer front contact of relay 2, left front contact of relay 12, left inner back contact of relay 11, lower next to outer back contact of relay 13 and through the winding of relay 12 to battery. Relay 12 also opens the operating circuit for the rotary magnet 10 and applies a busy tone from source 18 through the right inner front contact of relay 12 over the ring conductor to condenser 21, and thence to the calling subscriber's station.

If the called subscriber's line is idle the sleeve terminal of the line will be ungrounded and, therefore, relay 12 will not operate. However, a circuit is completed as follows for the operation of relays 13 and 14, after the release of relay 11. Battery 35 through the cut-off relay 14 of the called line, back contact of relay 16, sleeve terminal and brush of connector C, sleeve conductor 17, left outer back contact of relay 11, lower winding of relay 13, left back contact of relay 12 to ground at the lower outer front contact of relay 2. The operation of relay 14 opens the connection to battery and ground for the ring and tip conductors of line 4 respectively; and relay 13 is sufficiently energized to close its upper inner front contacts, thus closing a circuit from battery through its upper winding to ground at the lower inner front contact of relay 2. The energization of the upper winding of relay 13 causes the complete operation of this relay, which thereby connects an obvious ground to the sleeve conductor 17 to maintain the operation of the cut-off relay 14 and to guard the sleeve from seizure by other connector switches. Relay 13 also applies ringing current to the called subscriber's line in a circuit traced from ground through ringing source 19, upper next to inner front contact of relay 13, lower winding and back contact of ringing trip relay 20, lower outer front contact of relay 13, ring brush and terminal of connector C, ring conductor of subscriber's line 4, through the bell at substation B and back over the tip conductor of subscriber's line 4, tip terminal and brush of connector C, upper outer front contact of relay 13 to ground at the upper outer back contact of relay 20.

When the called subscriber removes the receiver in response to the ringing signal, relay 20 is sufficiently energized to close its upper inner front contact, thus closing a circuit from battery 70 through its upper winding to ground at the lower inner front contact of relay 2. The energization of the upper winding of relay 20 causes the complete operation of this relay and thereby opens the aforementioned ringing circuit. The opera-

tion of relay 20 also establishes a connection through its upper outer front contact and its lower front contact to battery and ground respectively for the tip and ring conductors through the windings of relay 3. Relay 3 operates through the called subscriber's loop and reverses, at its lower and upper armatures and contacts, the connection from battery and ground through the windings of relay 1 to the calling line. Talking battery for the calling subscriber is supplied from battery and ground, through the winding of relay 1 and talking battery for the called subscriber is supplied from battery and ground through the windings of relay 3. The talking circuit is completed through condensers 21. Condenser 22, which is used to divert a small part of the ringing current to the calling subscriber, as an indication that the called subscriber is being signalled, is short circuited upon the operation of relay 20.

When the connection is released by the calling subscriber hanging up his receiver, relay 1 releases, thereby causing the release of relay 2. Relay 2 causes the release of all operated relays and causes the operation of the release magnet 23. This circuit may be traced from ground at the back contact of relay 1, back contact of relay 2, upper back contact of relay 13, through upper closed contacts of vertical off-normal springs VON and thence through the winding of release magnet 23 to battery. When relay 2 releases the ground is removed from the sleeve conductor of selector S thereby restoring the selector and line finder LF to normal. The operation of the release magnet 23 restores the connector C to normal thereby opening the circuit for the release magnet at the vertical off-normal contacts VON. When relay 13 released ground was removed from the sleeve conductor 17, thereby releasing cut-off relay 14 which connects the line relay 15 and auxiliary line relay 16 to the tip and ring conductors of the called subscriber's line.

Let it be assumed that the subscriber at station B is tardy in replacing his receiver on the receiver hook, and that a second call is extended to the terminals of line 4 by a connector such as C. When the cut-off relay 14 releases as aforementioned, a circuit is closed to operate relays 15 and 16 which is traceable from ground through the left winding of relay 15, through winding of relay 16, right back contact of relay 14, tip conductor of line 4, through subset at station B, ring conductor of line 4, left back contact of relay 14 and through the right winding of relay 15 to battery. Relay 15 operated connects ground to the start lead 26 causing the line finder LF to operate and hunt for the subscriber's line 4 in the usual manner; and closes a circuit for operating the cut-off relay 14 when said line is found. Relay 16 in operating opens the sleeve circuit associated with the connector switch bank so that, until the line finder LF finds the line, the line is neither identified as a busy nor as an idle line in the connector switch bank due to the absence of ground and battery on said sleeve conductor. Accordingly a switch, such as connector C, seizing the line during this interval will not reject it as a busy line and, on the other hand, will not attempt to apply ringing as it would to an idle line. The application of ringing current to the line by a connector during this period would cause premature tripping of the ringing relay thereby resulting in a failure to complete the call. Should the subscriber replace the receiver on the receiver hook before the aforementioned line finder LF found the line, relays

15 and 16 would release. Relay 15 released opens the start lead 26 to the line finder LF thereby restoring the line finder in the usual manner. Relay 16 released closes the sleeve circuit, associated with the connector switch bank, so that the connector C, if not released by the new calling subscriber abandoning the call, will identify the line as idle and proceed to apply ringing current in an aforementioned manner.

If on the other hand the line finder LF finds the line and extends said line to selector S1 before the subscriber at station B replaces the receiver on the receiver hook, cut-off relay 14 will be operated in a circuit from ground on sleeve brush and terminal of line finder bank front contact of relay 15 and through winding of relay 14 to battery. Relay 14 in operating releases relays 15 and 16 as aforementioned; relay 16 released, connects ground at the line finder sleeve conductor to the sleeve conductor associated with the connector switch bank so that the connector C, if not released by the new calling subscriber abandoning the call, and provided the slow-to-release relay 11 has not released to disconnect the test relay 12 from the sleeve conductor 17, will identify the line as busy and proceed to apply busy tone to the calling line in an aforementioned manner. In case, however, the test relay 12 is already disconnected from the sleeve conductor 17 by the release of relay 11, the connector cannot function to identify the line until the receiver at the called station is replaced on the receiver hook, at which time the line relay (not shown) of selector S1 will release, thereby releasing line finder LF which causes the release of cut-off relay 14 in the usual manner. The removal of ground from the line finder sleeve, associated with the line, removes the aforementioned busy condition for the connector C and the latter (if the call has not been abandoned) identifies the line as idle and proceeds to apply ringing current as aforementioned.

Let it be assumed now that the subscriber at station B originates a call to a station (not shown) which is completed through line finder LF, selector S1 and other switches (not shown). The removal of the receiver from the hook at station B causes relays 15 and 16 to operate and function as aforementioned. Let it be assumed further that while the line finder LF is hunting for the terminals 24 of the subscriber's line a subscriber at station A has initiated a call for station B and that the associated connector C has seized the terminals of this line. The sleeve conductor associated with the connector switch bank is open at this time so that the connector C cannot identify the line as busy or idle. However, when the line finder LF finds the line and thereby causes the operation of cut-off relay 14, relays 15 and 16 release as aforementioned. Relay 16 released connects ground to the sleeve conductor, associated with the connector switch bank, so that the connector may now identify the line as busy, provided the test relay 12 is associated with the sleeve conductor 17 at this time. The connector, identifying the line as busy, applies the usual busy indication to the calling subscriber. However, if the test relay 12 has been disconnected from the sleeve conductor 17, before relay 16 releases, the presence of ground potential on the sleeve conductor will prevent the connector from applying ringing current to line 4.

Another method of guarding the line against seizure by the connector, while the line finder is

finding the line, is effected by connecting the front contacts of relay 16 to ground at terminals 27 so that the operation of relay 16 connects ground to the sleeve circuit, associated with the 5 connector switch bank, instead of opening said sleeve circuit as aforementioned. A connector seizing the line at this time identifies the line as busy and proceeds to transmit the usual busy indication to the calling subscriber, provided the 10 line is a direct subscriber's line and the connector, like the connector C, is not arranged for private branch exchange trunk hunting. However, the line may be one of a group of private branch exchange lines, and the connector may be arranged to hunt, in which case, finding the line 15 busy, it steps to the next line in the group.

Fig. 2 shows an alternate line circuit arrangement, which provides all of the features of the line circuit just described, with the exception of 20 the means provided in Fig. 1 for connecting ground to the connector bank sleeve conductor at terminals 27, during the line finder hunting period. By superimposing Fig. 2 onto Fig. 1 it is obvious that the circuit arrangements of 25 both figures are similar and that the only difference resides in a means for combining the functions of relays 15 and 16, said means being relay 25.

Although the invention has been disclosed in 30 connection with direct subscribers' lines, it should be understood that it is applicable to other types of lines such as private branch exchange trunks.

What is claimed is:

1. The combination in a telephone system of a 35 conversational circuit, a terminal for said circuit arranged to assume one electrical condition when the circuit is idle and another electrical condition when the circuit is busy, means effective if said circuit is in a calling condition to remove 40 the idle condition from said terminal so that the terminal presents neither the idle nor the busy condition, switching means for extending said circuit, and means effective in response to the extension of said circuit for placing the busy condition on said terminal.

2. The combination in a telephone system of a telephone line, a terminal for said line arranged to assume one electrical condition when the line is idle and another electrical condition 50 when the line is busy, means effective if the subscriber's receiver is off the hook to remove the idle condition from said terminal so that the terminal presents neither the idle nor the busy condition, switching means for extending said line, means effective in response to the extension of said line for placing the busy condition on said terminal, and means responsive to the replacement of the subscriber's receiver for removing the busy condition and replacing the idle condition 55 on said terminal.

3. In a telephone system, a line finder switch, a connector switch, a subscriber's line having a terminal in said finder switch and a terminal in said connector switch, means for placing an 60 idle test potential on said connector terminal, means responsive to the removal of the subscriber's receiver for starting said finder switch to find the line and for removing said idle potential from the connector terminal so that the 65 line appears neither busy nor idle to the connector switch, and means responsive to the finder finding said line for applying a busy potential to said connector terminal.

4. In a telephone system, a subscriber's line 70 having a test terminal, a circuit for applying an

idle potential to said terminal, means effective if the subscriber's receiver is off the switchhook for opening said circuit to remove said idle potential from the test terminal, such that the line appears neither idle nor busy, means for seizing said line, and means responsive to the seizure of said line for closing said circuit and for applying a busy potential to said terminal. 5

5. In a telephone system, a line having a test terminal, a circuit for applying an idle potential 10 to said terminal, means effective if the line is in a calling condition for opening said circuit to remove said idle potential from the test terminal, such that the line appears neither idle nor busy, means for seizing said line, means responsive to the seizure of 15 said line for closing said circuit and for applying a busy potential to said terminal, and means for releasing said seizing means and for removing the busy potential from said terminal. 20

6. In a telephone system, a line finder switch and a connector switch, a subscriber's line appearing in terminals in said line finder and in terminals in said connector, means for applying battery potential to the test terminal in the connector to identify the line as idle, means responsive to the removal of the subscriber's receiver for removing said potential from the connector test terminal and for starting said finder to find the line, means controlled by said finder 30 on seizing the line for applying a busy ground potential to said connector test terminal, means controlled by the subscriber for releasing said finder to restore said idle battery potential to said connector test terminal, and means responsive to 35 the seizure of said line by said connector for applying a busy ground potential to said test terminal.

7. In a telephone system, a finder switch and a connector switch, a subscriber's line appearing in 40 terminals in said finder and in said connector, means for applying an idle test potential to the test terminal of said line in the connector switch, means responsive to the removal of the subscriber's receiver for removing said idle potential 45 and for starting said finder to seize the line, means for operating said connector switch to seize the terminals of said line, means responsive to the subsequent seizure of said line by the finder for applying a busy potential to the test terminal in said connector switch, means controlled by the subscriber for releasing said finder to remove the busy potential from said test terminal and for reapplying the idle potential thereto, and means 50 in the connector switch responsive to the reapplication of said idle potential for signaling said subscriber. 55

8. In a telephone system, a connector switch, a subscriber's line appearing in terminals in said switch, means in said connector switch for testing the subscriber's line, means for sending a busy tone if the line tests busy, means for applying ringing current to said line if it tests idle, a non-numerical switch for extending said line in response to the receiver being off the switchhook at the station, means also responsive to the receiver being off the switchhook for removing the idle condition from the connector test terminal, and means responsive to the extension of said line by the non-numerical switch for placing a busy condition on said test terminal, said testing means in the connector being effective neither to send the busy tone nor to apply ringing current in case the connector seizes said line between the time said idle potential is removed and the time 70 75

said busy potential is applied to said test terminal.

9. In a telephone system, lines, automatic switches including a connector switch for establishing a connection between a calling line and a called line, said called line having terminals in said connector switch, means for applying an idle potential to the test terminal in said connector switch, means controlled by the calling party for effecting the immediate release of all of said switches, means controlled by the called party in case he delays the release of his line for withholding the application of said idle potential to said test terminals, means for seizing said called line, and means responsive to the seizure of said line for applying a busy potential to said test terminal.

10. In a telephone system, subscribers' lines, automatic switches including a connector switch for establishing a connection between a calling line and a called line, said called line having terminals in said connector switch, means for

applying an idle potential to the test terminal in said connector switch, means controlled by the calling party for effecting the immediate release of all of said switches, means controlled by the called subscriber's switchhook in case he delays the replacement of his receiver, whereby said called line will appear neither busy nor idle to a second connector switch subsequently seizing said called line, a non-numerical switch for seizing said called line in response to the closed condition thereof, means controlled by said non-numerical switch for placing a busy potential on the terminals of said line, means responsive to the replacement of said called subscriber's receiver for releasing the non-numerical switch and for replacing said busy potential by an idle potential on the test terminals of said called line, and means responsive to the replacement of said idle test potential for causing said second connector switch to signal the called subscriber.

FRANK NEWFORTH, Jr.
